UNITED STATES PATENT OFFICE.

WILLIAM OROZCO, OF CHICAGO, ILLINOIS.

AUTOMATIC WHISTLER.

Application filed January 31, 1927. Serial No. 164,776.

My invention relates to an electrically controlled whistle to be used as a warning device on automobiles. The object of my invention is to provide a musical whistle, adapted to play a tune, to replace the unmusical horns and other audible signals heretofore used on automobiles. A further object is to construct a musical whistle which can be readily rearranged at will to play any simple tune desired by the user.

Other objects will appear hereinafter.

The invention consists in the combination and arrangements of parts hereinafter described and claimed.

The invention will be best understood by reference to the accompanying drawings, forming a part of this specification, and in which,

Figure 1 is a side elevation of the whole device, part of the casing being broken away to show the interior arrangement of the resonance chamber of the whistle and the electrical connections to the commutator by means of which the pitch of the whistle is varied so as to produce a tune.

Figure 2 is a longitudinal section of the commutator, the connecting spirals and the driving mechanism.

Figure 3 is a section on the line 3—3 of Figure 2, showing a plan view of one connecting spiral.

Figure 4 is a perspective view of one of the removable segments for the commutator.

Figure 5 is a plan view of the commutator, the driving gear and clutch being removed on the line 5—5 of Figure 2, to show the parts below.

Figure 6 is a sectional view on the line 6—6 of Figure 5, showing details of the commutator brush and path.

Figure 7 is a detailed sketch of the commutator brush arm.

Figure 8 is a detailed sketch of the governor, a section being taken on the line 8—8 of Figure 2.

Figure 9 is a detailed end view of the mechanism on the rear of the commutator connector casing on the line 9—9 of Figure 1.

Figure 10 is an elevation of the whistle, part of the outer wall being broken away to show internal arrangement.

Figure 11 is a detailed sketch of the connecting spring on the end of the connecting

rods used to connect the commutator segments with the spirals.

Figure 12 is a sketch of a modification of my invention, showing two whistles arranged to play in harmony.

Figure 13 is a section on the line 13—13 of Figure 12, showing the cross arm and associated guide rods.

The preferred form of construction as illustrated in the accompanying drawings comprises a whistle 15 consisting of the usual form for steam or compressed air. Compressed air is supplied to it from a compressed air chamber (not shown) through the port 16. The compressed air chamber may be supplied with compressed air from any available source, as for instance from one of the cylinders of an automobile engine. The flow of air to the whistle is controlled by a suitable valve in the port 16, one such valve being illustrated in Figure 10.

A cylindrical chamber 17 is formed through the casing of the whistle at right angles to the port 16 in which a piston 18 operates with reciprocating motion. A bore 19 is drilled through piston 18 approximately of the same diameter as port 16. A piston rod 20 integral with the piston 18 extends beyond the frame of the valve and whistle. An internal rib or rim 21 is formed in the valve chamber 17, decreasing the diameter of the chamber to that of the piston rod 20. Beyond the rib 21 the diameter of the chamber again increases to accommodate a spring 22 which is seated against the rib 21. The diameter of the chamber again decreases to that of the piston rod 20, forming an outer rim 24. A collar 23 is fastened to the piston rod 20, against which the outer end of the spring 22 is seated, and it in turn rests against the rim 24. Normally the spring 22 holds the collar 23 against the outer rim 24, thus, holding the piston 18 so that the bore 19 occupies a position out of alignment with the port 16, the port 16 being closed by the piston 18.

When pressure is applied to the external end of the rod 20, the piston 18 and rod 20 move laterally, compressing the spring 22 between the collar 23 and the rib 21 until the bore 19 registers with the port 16, allowing the air from the compressed air chamber (not shown) to operate the whistle

15. When the pressure is released the spring 22 restores the piston 18 to its normal position, shutting off the air supply to the whistle 15.
- 5 Positioned vertically above the whistle 15 and fastened thereto by suitable brackets 25 (see Figure 1) is a resonance chamber 26, cylindrical in form, the top of which may be closed except for a small opening 10 27. Within the resonance chamber 26 is an embolus 28, adapted to close the resonance chamber 26, which normally rests on the supports 29 attached to the inner wall of the resonance chamber 26. The embolus 28 15 is free to move in the resonance chamber 26. It is evident that by moving the embolus 28 up and down within the resonance chamber 26 the length of the chamber is varied, which changes the pitch of the sound 20 produced by the whistle 15. The embolus 28 is caused to assume different positions in the resonance chamber 26 as hereinafter described.
- The portion of the resonance chamber 26, 25 which is below the rests 29, may be made of any rigid material which is suitable; the part of the resonance chamber 26 which is above the rests 29 is composed of a series 30 of electromagnets 30, composed of coils of insulated wire capable of conducting a current of electricity, the several electromagnets 30 being separated from each other by rings 32 of insulating material. The electromagnets 30 may be solenoids or they may 35 have cores 31 of magnetic material separated from each other by rings of non-magnetic material 32. The windings of the magnets 30 are electrically connected together in series, connection being shown at 33, in such 40 a manner that a current of electricity flowing through the windings will create magnetic fields, one for each magnet 30, having north poles in the same direction. The windings of the magnets 30 are so designed 45 that each one, starting with the one nearest the supports 29, creates a stronger magnetic field than the one next preceding it, when a current of electricity is flowing through all of the magnets 30 in series. At the point 50 33 where the winding of each electromagnet 30 is connected to the winding of the next succeeding one, an electric connection is made to one of the binding posts 34 on the casing 35 of the commutator connecting spirals 40 as hereinafter described. The open end of the winding of the first magnet 30 of the series is connected to one side of an electric switch 100, the other side of 55 which is connected to a grounded source of E. M. F. 37, and the open end 38 of the winding of the last magnet 30 is connected to one of the above mentioned binding posts 34. When the circuit is completed to any 60 one of the binding posts 34, as hereinafter described, the magnet 30 connected thereto

is energized and also all the magnets 30 between it and the supports 29, creating thereby a magnetic field within the resonance chamber 26 located within the magnets 30 energized. The embolus 28 is made of magnetic material and is free to move in the resonance chamber 26. Since the magnetic field within the resonance chamber 26 thus created is strongest at the location of the energized magnet 30, which is farthest from the rests 29, that is to say, the highest magnet 30 energized in the resonance chamber, the embolus 28 is moved up in the resonance chamber 26 and takes up a position in line with the highest magnet 30 energized. The positions which the embolus 28 is made to assume by this means are spaced so as to cause the whistle 15 to play the notes of a musical scale, a sufficient number of notes being provided to permit simple tunes to be 85 played.

Tunes are played automatically on the whistle 15 by completing electric circuits through the various magnets 30 in succession, as required to produce the notes of the tune and for varying lengths of time, as required by the rhythm of the tune, by means of the commutator 39, rotating commutator brush 42 and a system of connector spirals 40 and rods 50 which are enclosed 95 in the casing 35. The operation of this part of this invention will best be understood by referring to Figures 2, 3 and 5.

The commutator 39 is a disc of a rigid di-electric material through which is cut a spiral path 41. The outer part of the path 41 is of sufficient width to accommodate and guide the brush 42, which is composed of material capable of conducting a current of electricity, preferably carbon. The inner part of the path widens out as it approaches the inner surface of the commutator 49. In the inner portion of the path 41 are placed segments 43 of conductor material shaped to fit the lower portion of the path, and of varying length (see Figure 4). The segments 43 are separated from each other by small segments of insulating material 44, which are the same shape as segments 43 in cross section, are adapted to be placed in the lower portion of the path 41, and are narrower than the brush 42 so that the brush 42 will always make connection with at least one segment 43. The commutator 39 is mounted vertically upon the front panel 105 of the commutator connector casing 35. The panel 45 is made of rigid di-electrical material and has cut therein a spiral slot 46, slightly narrower than the inner part of the path 43, which serves to hold the segments 43 and 44 in place and at the same time affords means of connecting the segments 43 to the spiral connectors 40 within the casing 35.

The commutator 39 may be removed from 130

the connector casing as hereinafter described.

The spiral connectors 40, hereinafter referred to as spirals 40, are made of resilient material which is a good conductor of electricity. They are positioned parallel to each other with an air space between each turn, and parallel to the commutator 39 so that the spaces between the turns of the spirals 10 are aligned with path 43 of the commutator 39. They are affixed at the outer end by means of screws 41 to an arcuate projection 47 with the panel 45 and at the center by the screws 48 to projection 49 from the 15 panel 45. Each spiral 40 makes a sliding connection with a binding post 34 which extends through a suitable hole in the wall of the casing 35. By this construction each spiral 40 is electrically insulated from the 20 other spirals 40 but is electrically connected with the winding of one electromagnet 30. Since there is one spiral 40 for each electromagnet 30, each spiral 40 represents one note in the scale which the whistle 15 is capable 25 of playing.

Each segment 43 in the commutator 39 may be connected to any spiral 40 as required by the tune to be played by means of the rods 50. The rods 50 are made of conductor material surrounded by a sheath of insulation. One end is threaded to screw into the screw hole 51 in the segment 43. To the other end is secured a suitable contact spring, the one illustrated being composed 35 of 4 spring sections 52, (see Figure 11) which are secured at one end to the rod 50, and bend outward from the rod 50, then parallel to the rod 50 for a portion of their length, then inward toward the rod, and are finally again bent parallel to the rod 50 so that the ends lie adjacent to the sides of the rod 50 but are not secured thereto. As will be readily perceived these springs are capable of yielding to lateral pressure to decrease 45 the diameter at the end of the rod 50. In order to connect any segment 43 of the commutator with any spiral 40, a rod 50 is used of such a length that when the screw end is screwed into the segment 43, the spring 52 on 50 the end of the rod makes contact with the desired spiral 40. The rod 50 is thrust through the interstices of the intervening spirals 40, the spring 52 yielding and allowing it to pass, but makes good electrical contact on the two adjacent turns of the spiral 40 which coincides with the end of the rod, because of the pressure exerted by the springs 52.

Suitable mechanical means for moving the 60 brush 42 around the commutator path 41 are provided as follows:

Power from any available part of the automobile is transmitted through the flexible driving shaft 53, the universal joint 54, 65 system of gears 55, 56, 57, and 58 and the

clutch 59, when closed, to the shaft 60. The shaft 60 is composed of conductor material. It is supported by the sleeve 67 in which it is free to rotate and to move laterally, sufficiently to open and close the clutch 59. It is controlled by the bell crank 61 to one arm of which it is fastened by means of the hook 62. To the other end of the shaft is fixed one element of the positive clutch 59. The shaft 60 may be grounded through the slide- 75 able brush 64 and binding post 65, if the engine of the automobile does not already supply a ground through the system of driving gears.

The sleeve shaft 67 is also rotatable but is 80 not capable of lateral motion. It is supported and held in place by the bushing 63 and the collars 70 and 71, all fastened to the sleeve 67, and turns in roller bearing 68 in the casing 35 and the panel 45. Motion is 85 imparted to the sleeve shaft 67 by means of the friction clutch 69. Normally the springs 70 hold the friction clutch 69 out of the engagement of the gear 58, but when the operation of the bell crank lever 61 closes 90 the clutch 59, the gear 58 moves laterally also, sufficiently to compress the springs 70, thereby closing the clutch 69 and causing the sleeve 67 to rotate with the shaft 60. Keyed to the sleeve 67 by means of the key 95 71 is a collar 72 to which is fastened the brush arm 73. The motion of the sleeve 67 is thereby imparted to the brush arm which rotates, carrying the brush 42 with it. Also, keyed to sleeve 67 by means of the key 74 100 105 is a suitable governor, provided to cause the brush arm 73 to rotate approximately at a constant speed, no matter what the speed of the automobile engine. The governor here illustrated consists of a collar and disc 75 which are free to slide on sleeve 67; four weights 76 attached to bowed springs 77 are secured to the collar 75 at one end, and at the other end to the collar 78 which is pinned to the sleeve 67; a 110 ring shaped brake 79 is mounted on the arm 80 secured to the inner wall of the casing 35, parallel with but a small distance from disc 75. When the speed of the sleeve 67 exceeds a pre-determined rate the centrifugal 115 force developed thereby spreads the weights 76, causing the disc and collar 75 to move along the sleeve 67 until the disc 75 comes in contact with the brake 79. The friction developed thereby slows the speed of the 120 sleeve 67, the speed of the shaft 60 not being affected since the rotary motion is imparted to the sleeve 67 by means of the friction clutch 69. It is understood that other mechanical means may be substituted for those 125 just described to cause brush 42 to travel over the commutator, without departing from the spirit of the invention.

The brush arm 73, as will best be seen by reference to Figure 7, is secured to the col- 130

lar 72 at a distance equal to the radius of the commutator 39 from one end, and a short distance inward from the other end. In the longer arm of the brush arm 73 is a slot 81 of such width as to accommodate the brush 42 and of sufficient length to permit the brush 42 to follow the spiral path 41 in the commutator 39 from the innermost to the outermost part, as the arm 73 rotates. Two retractile springs 82 are secured at one end to the shorter arm of the brush arm 73, and at the other end to the brush 42, adapted to draw the brush 42 back to the center of the spiral path 41 when it has reached the outer end thereof, as hereinafter described.

The brush 42, as will be seen by reference to Figure 6, consists of the carrier 96, the brush proper 86, and a pair of fingers 90. The carrier 96 is composed of conductor material, such as cast iron, and is approximately T shape in cross section. The narrower portion 83 is adapted to move with reciprocating motion within the slot 81 in the brush arm 73; the wider portion 84 is adapted to ride upon the brush arm 73 and thereby support the brush 96, it being wider than the slot 81. To the portion 84 are attached two lugs 85, to which are secured the ends of the retractile springs 82 above mentioned.

In the narrower portion 83, of the carrier 96, a recess 98 is formed, within which the brush 86 is movably secured by means of the screw 97. The brush 86 is composed of conductor material, preferably carbon, and is cylindrical in shape, the diameter of the outer part being suitable to fit in the path 41 of the commutator 39 and make contact with the segments 43 and 44 therein. At a sufficient distance from the outer end of the brush 86 to be well above the edge of the path 41, a ring 88 is formed of greater diameter than the end of the brush 86. The upper part of brush 86 is adapted to fit movably into the recess 98 but does not reach to the top of said recess, a space being allowed sufficient to raise the brush 86 out of the path 41. The brush 86 is supported by the head of the screw 97 which bears against the outer surface of the portion 84 of the carrier 82, being firmly held in place by the spring 87 which is compressed between the inner surface of the portion 84 of the carrier and the inner portion of the brush 86. In the sides of the carrier 82 adjacent to the sides of the carrier arm 73, are cut two slots 89 which accommodate a pair of fingers 90 pivoted on the screws 91, their lower ends bent inwardly and positioned a small distance from the ring 88 on a brush 86. To the ends of the fingers 90 are attached the lugs 92 which project toward the center of the commutator 39. The upper ends of the fingers 90 project above the top of the carrier 82 and have attached thereto pins 93

between which is secured the spring 94, serving to hold fingers 90 in their closed position.

On each side of the path 41 at the outer end thereof is mounted an incline 95. When the brush 86 has traveled the whole length of path 41 from the center of the commutator 39 to the outermost turn, the ring 88 of the brush 86 encounters the incline 95 and is raised thereby against the pressure of the spring 87, compressing it until the ring 88 strikes against the fingers 90, which are separated by the pressure until the curved ends engage the ring 88 and hold the brush 86 out of the path 41. The retractile springs 82 are thus permitted to contract, drawing the carrier 96 together with the brush 86 back to the center of the commutator 41, where the projections 92 are engaged by a pair of projections 131 attached to the collar 72, positioned below the slot 81 and projecting in the same direction as said slot. Projections 131 spread the fingers 90, disengaging them from the ring 88, and the spring 87 returns the brush 86 to the path 41 at its beginning. Since the brush 86, carrier 82, brush arm 73 and all associated parts are made of conductor material, and since the shaft 60 is grounded, the brush 86 is also grounded.

The commutator 39 may be removed from the panel 45 by removing the cotter pin 98 and the pins which hold the collar 72 to the sleeve 67, and then removing the clutch 57, gear 58, and collar 72 to which is attached the brush arm 73 with its associated parts. The screws 99 are removed from the panel 45 and the commutator 39, panel 45 and associated segments 43 and 44, rods 50 and connector spirals 30 are removed from the casing 35 together. To re-arrange the commutator segments 43 and 44 the screws 130 in the commutator are removed, allowing the commutator 39 to be separated from the panel 45, after which the parts may be re-assembled.

Suitable means for starting the whistle, and co-ordinating the operation of the whistle and the controlling commutator are provided, and the means here described are mechanical; in practice, however, electrical means could well be substituted therefore. When the button 100 is pressed down, an electric switch 101 is closed to connect the source of E. M. F. 37, one electrode of which is grounded, to the windings of the electromagnets 30. At the same time the movement imparted to the rod 102 operates the lever 103 and the bell crank 61, connected together by the toggle joint 132, simultaneously, applying pressure to the piston rod 20 to open the air valve of the whistle 15 as previously described, and close the clutches 59 and 69, due to the pull on the shaft 60 as previously described. When the pressure is removed

from the button 100 a spring (not shown) retracts the rod 102, opening the clutches 59 and 69, and closing the air valve of the whistle 15.

5 In use the whistle functions as follows:

Pressure on the button 100 functions mechanically as shown or electrically connecting battery to the magnets which control the pitch to the whistle, closing the clutches 59 and 69, and opening the air valve of the whistle 15.

10 The system of gears 55, 56, 57 and 58 are constantly in motion when the automobile engine is running. Hence, the closure of the clutches starts the brush arm 73 rotating at a constant speed as controlled by the governor. The brush starts from the position in which it stopped after the last use and follows the path 41 in the commutator 39, making contact with each segment

15 42 and 43 forming the floor of the path in turn, and connects the ground thereto, thereby completing an electric circuit from the ground through the shaft 60, brush arm 73, brush 42, commutator segment 43, associated rod 50 and connector spiral 40, winding of the associated magnet 30, windings of all magnets 30 below it in the resonance chamber 26, switch 100 to the grounded source of E. M. F. 37. The magnets 30 energized

20 in the sequence determined by the connections between the connector segments 43 and the spirals 40, cause the embolus 28 to change its position in the resonance chamber 26, in accordance therewith as already described.

25 The embolus 28 remains in each position in the resonance chamber 26 for a length of time determined by the size of the successive segments 43 in the commutator path 41. The successive positions of the embolus 28

30 in the resonance chamber produce a consequent variation in the pitch of the whistle 15. In this manner a tune is played upon the whistle automatically, the rhythm of the tune being produced by the length of the

35 commutator segments 43, and the melody, by the order in which segments 43 are connected to the spirals 40. Since each of said spirals corresponds to a note of the whistle, as has been described, the notes may be

40 played in any succession by selecting a rod 50 for each successive segment 43 of suitable length to connect such segment to the spiral 40 which controls the desired note.

45 It will be noted that by means of the construction herein described the commutator may be arranged to play any tune which is within the range of the notes provided for the whistle, by the selection and arrangement of segments 43 and rods 50. When

50 pressure is removed from the button all of the parts are restored to their normal positions.

55 Only so much of the tune is played at one time as can be played in the length of time the button is pressed. When it is again op-

erated the tune is resumed where it left off on the last operation. When the user becomes tired of one tune the commutator may be removed as already described and the segments and connections thereto rearranged to play another tune.

60 Figures 12 and 13 show a modification of my invention, involving the addition of a second whistle designed to play a note in harmony with the notes of the tune. In

65 Figure 12, 110 is the commutator connector case constructed as already described, the commutator and brush arm, etc., not being shown; 111 is the controlling mechanism, the same as already described; 112 is a grounded

70 source of the E. M. F.; 113 and 114 are two whistles, similar to the whistle 15 already described, the air valves of which are operated together by means of a single piston

75 rod 115; 116 is a resonance chamber associated with the whistle 113, equipped with an electromagnet as already described; 117 is the resonance chamber associated with the whistle 114 and consists merely of a hollow

80 cylinder supported above the whistle; 118 is an electrically controlled embolus similar to that already described, to which is attached a rod 120 by means of the nuts 121 and 122;

85 119 is an embolus associated with the whistle 114 and is adjustably attached to the rod 123 by means of the nuts 124 and 125, the rod 123 being threaded throughout its length. The rods 112, 120 and 123 are rigidly secured together at their upper ends by means

90 of the cross arm 126. The embolus 110 therefore, moves with the embolus 118, the cross arm 126 being guided and controlled by rods 127 secured to the bracket 128 between the supporting brackets of the resonance chambers 113 and 117. The embolus

95 119 is adjusted on its associated rod 123 so that it causes the whistle 114 to play a note always in harmony with any note played by the whistle 113. By adjusting the position

100 of the embolus 119 on the rod 123 it is evident that the whistle 114 can be made always to play a note, a musical third or sixth above or below any note played by the whistle 113, or any other interval which may appeal to the fancy of the user.

105 Having described my invention, what I claim as new and desire to secure by Letters Patent is:

110 1. In a device of the class described, a sound producing member, a co-acting pitch varying member, means for automatically controlling said pitch varying member, means for co-ordinating the operation for

115 said sound producing member and said controlling means adapted to permit the device to be operated and stopped at will, substantially as described.

120 2. In a device of the class described, a sound producing member, a co-acting pitch varying member, means for automatically

controlling said pitch varying member in a pre-determined manner, means for co-ordinating the operation of said sound producing member and the said controlling means adapted to permit the device to be operated and stopped at will, substantially as described.

3. In a device of the class described, a sound producing member, a co-operating resonance chamber, means for varying the volume of said resonance chamber to vary the pitch of said sound producing member, means for automatically controlling said varying means, means for co-ordinating the operation of said sound producing member and the said controlling means adapted to permit the device to be operated and stopped at will, substantially as described.

4. In a device of the class described, a sound producing member, a co-operating resonance chamber, means for varying the volume of said resonance chamber to vary the pitch of the said sound producing member in a pre-determined manner, means for automatically controlling said varying means, means for co-ordinating the operation of said sound producing member and said controlling means adapted to permit the device to be operated and stopped at will, substantially as described.

5. In a device of the class described, a sound producing member as a whistle; a co-operating resonance chamber; within the said resonance chamber a movable embolus, adapted to close said resonance chamber at various heights whereby to be able to vary the pitch of said sound producing member; means for automatically controlling the position of said embolus and said resonance chamber in a pre-determined manner; means for co-ordinating the operation of said sound producing member and said embolus controlling means, adapted to permit the device to be operated and stopped at will, substantially as described.

6. In a device of the class described, a sound producing member as a whistle; a co-operating resonance chamber; a moveable embolus within said resonance chamber adapted to vary the volume of said resonance chamber, thereby varying the pitch of said whistle, and adapted to be actuated by a magnetic field; means for producing a magnetic field within said resonance chamber, variable in extent throughout the length of said resonance chamber and increasing in intensity as it extends higher in said resonance chamber, means for varying the extent of said magnetic field automatically in a pre-determined manner; means for co-ordinating the operation of said sound producing member and said means for controlling the magnetic field, adapted to permit the device to be operated and stopped at will, substantially as described.

7. In a device of the class described, a sound producing member as a whistle; a co-operating resonance chamber comprising a plurality of electromagnets positioned one above the other in said resonance chamber, increasing in strength from the lowest to the highest, the windings of said electromagnets being connected together in series, and one end of the winding of each of said electromagnets being connected to a connector spiral; a movable embolus within said resonance chamber adapted to vary the volume of said resonance chamber and adapted to be actuated by said electromagnets; means for completing electric circuits through the said connector spirals in a pre-determined order; means for co-ordinating the operation of said whistle and said means for completing electric circuits whereby both may be simultaneously started and stopped at will, substantially as described.

8. In a device of the class described, a sound producing member as a whistle; a co-operating resonance chamber having a plurality of electromagnets positioned one above the other therein, the windings of said electromagnets connected together in series adapted for producing a magnetic field increasing in strength from one and to the other of said resonance chamber, and one end of the windings of each of said electromagnets connected to one of a series of connector spirals hereinafter mentioned; a movable embolus within said resonance chamber adapted to vary the volume of said resonance chamber and adapted to be actuated by said electromagnets; a source of E. M. F. removably connected to said electromagnets; a series of connector spirals above mentioned arranged in parallel spaced relation with each other and with a dielectric commutator, and electrically insulated from each other; a spiral path cut in said commutator with conductor and insulator segments of various sizes removably positioned in the floor thereof; a plurality of connecting rods, each of said rods being removably attached at one end to the conductor segment of said commutator and said rods being adapted to pass through the interstices of the intermediate connector spirals and to make electrical contact through connector springs attached to said rods with one spiral connector; a co-acting commutator brush adapted to travel over the said commutator path and to complete electrical circuits through the said conductor segments, and associated rods and spirals in order, and the windings of said electromagnets in succession whereby to cause said whistle to play a tune; means for actuating said commutator brush and for returning said commutator brush to the beginning of the path when it has reached the end thereof; means for co-ordinating the operation of the said whistle and said commu-

tator brush so that the whistle will play and stop at the will of the user, substantially as described.

9. In combination with a sound producing member, the pitch of which may be varied electrically, a plurality of connector spirals insulated from each other and arranged in spaced parallel relation to each other, each of said spirals being electrically connected 10 to the sound producing member so that the completion of an electrical circuit through each spiral causes the sound producing member to produce a different note in the musical scale; means for making electrical connections to said spirals in a manner to close electrical circuits through the said spirals in a pre-determined order, whereby to cause said sound producing member to play a tune, substantially as described.

10. In combination with a sound producing member, the pitch of which may be varied electrically, a plurality of connector spirals arranged parallel to each other, insulated from each other and spaced at regular intervals, electrically connected to the sound producing member so that the completion of an electrical circuit through each spiral causes the sound producing member to produce a different note in the musical scale; a plurality of connector rods of various lengths, insulated throughout their length and having connector springs secured to the ends of said rods adapted to pass through the intervening spirals and make electrical contact with the one which coincides with the end thereof, the other end of said rods being adapted to be detachably connected to the segments of the commutator, said rods and associated springs being adapted to make a connection between any spiral and any commutator segment; a commutator composed of di-electric material in which is cut a spiral path; removable connector and insulator segments of various sizes in said commutator path, said segments being connected to any required spiral by means of said rods; a co-acting commutator brush adapted to travel over said commutator path to complete electrical circuits through said commutator segments, rods and spirals, in succession thereby causing the sound producing member to play a tune; means for actuating said commutator brush and for returning said commutator brush to the beginning of said path when it has reached the end thereof so that when said brush passes over the said commutator segments said sound producing member will play a tune, which tune can be changed by changing the sizes of said segments and rearranging said rods and connections, substantially as described.

11. In a musical instrument, the pitch of which can be controlled electrically, means for varying the pitch in a pre-determined

manner, comprising a commutator having a spiral slot cut therein; insulator and conductor segments in said slot; a series of conductor spirals arranged in parallel spaced relation to and insulated from each other, 70 each of said spirals being electrically connected to said musical instrument in a manner to cause said instrument to play a different note in the musical scale, whenever a circuit is completed therethrough; connector rods having springs adapted for connection with said spirals, attached to one end thereof, the other end of said rods adapted for detachable connection with said commutator segments, said rods being of various lengths and insulated between the commutator segment and the connector spring, whereby, by means of a rod of suitable length, any commutator segment may be connected to any spiral; and a cooperating 80 commutator brush adapted to make electric contact with each commutator segment in turn, substantially as described.

12. In a musical instrument, the pitch of which can be varied electrically, means for 90 playing a tune thereon comprising a commutator having removable segments alternately conducting and insulating; a co-acting commutator brush, and means for causing said brush to pass over said commutator 95 segments; a plurality of connector elements, each electrically connected to said instrument in a manner to play a single note in the musical scale when a circuit is closed therethrough; and means for detachably 100 connecting any of said commutator segments with any of said connector elements, substantially as described.

13. In a musical instrument, the pitch of which can be varied electrically, means for 105 playing a tune thereon comprising a commutator having alternate conductor and insulator segments; a co-acting commutator brush and means for propelling said brush over said commutator segments; a plurality of 110 conductor spirals arranged in parallel spaced relation to each other and said commutator, each of said spirals being electrically connected to said musical instrument in a manner to play a single note in the musical scale 115 when an electric circuit is closed therethrough and means for connecting said spirals to said conductor segments of said commutator, substantially as described.

14. In a musical instrument, the pitch of which can be varied electrically, a commutator formed of dielectric material; a spiral slot cut in said commutator; removable segments of dielectric and conductor material adapted to fit into said slot; detachable 125 means for connecting the said conductor segments to said instrument; a co-acting commutator brush adapted to fit into said slot; means for causing said brush to move in said slot making contact with said commu- 130

tator segments whereby to close electrical circuits controlling the pitch of said instrument; means for returning said brush from the end of said slot to the beginning thereof, substantially as described.

15. In a device of the class described, a plurality of sound producing members as whistles, each associated with a co-acting resonance chamber; a movable embolus within each resonance chamber; electromagnetic means for controlling the position of one of said emboli within its associated resonance chamber; means for causing said other emboli to change position in their associated resonance chambers in a fixed relation to the change of position of said electrically controlled embolus, substantially as described.

16. In a device of the class described a plurality of sound producing members as

whistles, each associated with a co-acting resonance chamber; a movable embolus adapted to vary the pitch of said sound producing members within each resonance chamber; electromagnetic means for controlling the position of one of said emboli within its associated resonance chamber; a rod affixed to each of said emboli at one end, the other end of said rod extending beyond its associated resonance chamber, said rods being mechanically connected together so that the emboli associated therewith move within their resonance chambers in a fixed relation to the movement of said electrically controlled embolus, substantially as described.

In testimony whereof I have signed my name to this specification.

WILLIAM OROZCO.
